UNITED STATES PATENT OFFICE

96,934

DESIGN FOR A RADIANT HEATER

Betty W. Pruitt, Columbus, and Graham Walker,
Mount Vernon, Ohio

Application July 19, 1935, Serial No. 57,730

Term of patent 7 years

To all whom it may concern:

Be it known that we, Betty W. Pruitt and Graham Walker, citizens of the United States, residing at Columbus, Franklin County, Ohio, and Mt. Vernon, Knox County, Ohio, respectively, have invented a new, original, and ornamental Design for Radiant Heater, of which the following is a specification, reference being had to the accompanying drawing, forming a part thereof.

Fig. 1 is a front elevation of a radiant heater showing our new design;

Fig. 2 is a top plan view thereof;

Fig. 3 is a side elevation.

We claim:

The ornamental design for a radiant heater, as shown.

BETTY W. PRUITT.
GRAHAM WALKER.
